Inventor

Alonzo J. McMaster

UNITED STATES PATENT OFFICE.

ALONZO J. McMASTER, OF LOCKPORT, NEW YORK.

CAMPING-VEHICLE.

SPECIFICATION forming part of Letters Patent No. 453,205, dated June 2, 1891.

Application filed July 19, 1890. Serial No. 359,345. (No model.)

To all whom it may concern:

Be it known that I, ALONZO J. McMASTER, a citizen of the United States, residing at Lockport, in the county of Niagara and State 5 of New York, have invented a new and useful Improvement in Camping-Vehicles, (in addition to an improvement in camping-vehicles for which I obtained Letters Patent No. 404,101, dated May 28, 1889,) of which the following is a specification.

My improvement consists in this: that I make a camping-vehicle of sufficiently greater length to form a room in front, which shall be a combination of an observation-room, 15 smoking-room, and kitchen, in combination with the above-named camping-vehicle, with a revolving seat upon either side of the central passage-way, as shown in accompanying drawing, which shall form a comfortable seat 20 when in use as an observation and smoking room, and when turned over will form a

kitchen-table with bottom of the seat, and disclose stoves in a hollow seat-support for cooking purposes.

Reference being had to the accompanying 25 drawing, A represents a seat in position, and B the same turned over for use as a table.

A stove for cooking is shown at C.

I am aware that prior to my invention rooms have been used for observation, smoking, and cooking purposes. I therefore do not 30 claim such broadly; but

What I do claim as my invention, and desire to secure by Letters Patent, is—

In a camping-vehicle, a combined observa- 35 tion-room, smoking-room, and kitchen, having the revolving seats A A and stoves C C, as set forth.

ALONZO J. McMASTER.
